UNITED STATES PATENT OFFICE

MORIS HIRSHFIELD, OF NEW YORK, N. Y., ASSIGNOR TO E-Z WALK MFG. CO., OF NEW YORK, N. Y., A FIRM

COMBINED ARCH-SUPPORT AND ANKLE-STRAIGHTENER.

1,053,600.

Specification of Letters Patent No. 1,053,600 Patented Feb. 18, 1913.

Application filed January 12, 1912. Serial No. 670,761.

To all whom it may concern:

Be it known that I, Morris Hirshfield, a subject of the Czar of Russia, residing at New York city, in the county and State of New York, have invented certain new and useful Improvements in a Combined Arch-Support and Ankle-Straightener, of which the following is a specification.

My invention relates to an improved form 10 of combined arch support and ankle straightener, and is designed to provide a device which, in use, performs the double function of supporting what are known as the falling arches of human feet and 15 straightening ankles having a tendency to turn inwardly.

The primary object of the invention is to construct an arch support and ankle straightener which may be cheaply manufactured and which shall be thoroughly efficient in operation.

Two embodiments of the invention are shown in the accompanying drawing, whereon—

25 Figure 1 is a top plan view of the preferred form of the device; Fig. 2 is a longitudinal section thereof on line 2—2 of Fig. 1; Fig. 3 is a transverse section on the line 3—3 of Fig. 1; Fig. 4 is a longitudinal section of a modified form of the invention; and Fig. 5 is a transverse section on the line 5—5 of Fig. 4.

Referring by reference characters to the drawing and particularly to Figs. 1 to 3 thereof, 10 designates a sole plate made of tough pliant material such as leather, the sole plate being designed to lie adjacent the sole of the foot of the user. This sole plate is curved upwardly from the heel portion *a* to the highest point *b* of the curve which is adapted to lie under the arch of the foot, and from the point *b* the plate curves somewhat abruptly downwardly at *c* toward the portion of the device designed to lie under the ball of the foot. At its inner edge and midway between the heel and ball portions, the plate 10 is provided with a lateral extension 10^a curving upwardly from the plane of the plate 10. The purpose of this lateral extension will be presently described.

Lying under and adjacent the plate 10 is a plate 11 which performs the double func-

tion of supporting the arch and straightening the ankle. The general configuration of the plate 11 is shown in dotted lines in Fig. 55 1, the plate being somewhat elliptical and having a lateral extension 11^a which curves upwardly from the plane of the plate 11. The plate 11 has the general curvature of the sole plate 10, the extension 10^a overlying 60 and extending somewhat beyond the extension 11^a so as to protect the foot of the user from contact with the latter. The plate 11 is made of metal the body portion thereof being yielding while the upwardly curved 65 extension 11^a is rigid.

In the preferred form of the invention the device includes a rigid base plate 12 of suitable metal, this base plate being curved generally in the same manner as the sole plate, 70 the two plates being secured together preferably by a series of three rivets 13 or the like at or near the ball end of the device and by a single rivet 13 at or near the heel end of the device. 75

At the forward end the plate 11 is secured to both the sole plate and base plate by one of the series of three rivets 13, but at its rear end the plate 11, which is substantially shorter than either of the plates 10 and 12, 80 is secured to the plate 10, only, by a rivet 14 or other suitable fastening means.

It will be noted from Fig. 1 that the plate 11, which has been described as being substantially elliptical in form, is provided near each end of the ellipse with a plurality of perforations 11^b, the perforations being symmetrically arranged. In the illustration of Fig. 1 the plate 11 is assumed to be used in connection with a shoe for the right foot. 90 But, one perforation 11^b is visible (Fig. 1) at either end of the plate 11, the other perforation at each end being engaged by one of the rivets 13 or 14.

In use the device is placed in a shoe or other article of footwear with the portion *a* under the heel of the foot, the portion *b* under the arch and the portion *c* under the ball. The body portion of the plate 11 serves as the yielding arch support while the 100 upwardly curving rigid portion 11^a presses against the inner side of the arch and thus tends to straighten into normal position ankles having a tendency to turn inwardly.

or toward each other. Owing to the fact that at one end the plate 11 is fastened to the sole plate 10 only, a yielding connection is established whereby the plate 11 has sufficient play to permit it to adjust itself to the position best suited to the shape of the foot of the wearer.

In the modified form of the invention the rigid plate 12 is omitted and a single plate 10^c is used as an arch support and ankle straightener. Referring to Figs. 4 and 5, the numeral 10^c designates the sole plate having the lateral upwardly curving extension 10^d. Underlying the sole plate 10^c and secured thereto by rivets 13^c is a single arch support and ankle straightening plate 11^c, having the lateral upwardly curving extension 11^d which is covered and slightly overlapped by the extension 10^d of the sole plate 10^c. The general curvature of the modified form of the device is exactly like that of the preferred form and its function, when in use, is also the same.

Having now described my invention what

I claim as new and desire to secure by Letters Patent is:—

In a device of the character described, the combination with a sole plate curved to conform substantially to the normal shape of the sole of a human foot, said plate having a lateral upwardly curved extension, of a rigid base plate secured at two ends to said sole plate, an intermediate plate shorter than said sole plate and conforming generally in curvature thereto, said intermediate plate being of yielding material having a lateral upwardly curving extension of rigid material, and means whereby said intermediate plate is secured at one end to both said other plates and at its opposite end is secured only to said sole plate.

In testimony whereof I have affixed my signature in presence of two witnesses.

MORRIS HIRSHFIELD.
